W. A. FOX.
GUIDING DEVICE FOR SEWING MACHINES.
APPLICATION FILED JULY 6, 1908.

925,471.

Patented June 22, 1909.

UNITED STATES PATENT OFFICE.

WILBER A. FOX, OF POTSDAM, NEW YORK, ASSIGNOR TO GREIG MUSLIN UNDERWEAR COMPANY, OF POTSDAM, NEW YORK, A CORPORATION OF NEW YORK.

GUIDING DEVICE FOR SEWING-MACHINES.

No. 925,471.

Specification of Letters Patent.

Patented June 22, 1909.

Application filed July 6, 1908. Serial No. 442,087.

To all whom it may concern:

Be it known that I, WILBER A. FOX, a citizen of the United States, residing at Potsdam, in the county of St. Lawrence and State of New York, have invented certain new and useful Improvements in Guiding Devices for Sewing-Machines, of which the following is a specification, reference being had to the accompanying drawings.

10 This invention relates to new and useful improvements in guiding devices for stitching machines; and it is an object of the invention to provide a novel device of this character adapted to be employed in conjunction 15 with attachments to sewing machines, as a tucker attachment, for example.

It is also an object of the invention to provide a novel device of this character which can be adjusted to goods of different widths

20 and which can be readily moved to position the fabric with relation to the tucker attachment.

A further object of the invention is to provide a novel device of this character so 25 mounted as to be adjustable relatively to the tucker attachment, as may be required by the necessities of practice.

Another object of the invention is to provide a novel device of this character which 30 will be simple in construction, handy and efficient in operation and comparatively inexpensive to manufacture.

In describing the invention in detail reference will be had to the accompanying drawings forming part of this specification wherein like characters of reference denote corresponding parts in the several views and in which—

Figure 1 is a plan; Figs. 2, 3 and 4 are sections on lines 2—2, 3—3 and 4—4 of Fig. 1, respectively; and Fig. 5 is a fragmentary view illustrating a detail hereinafter referred to.

In the drawings 1 denotes a base-plate 45 adapted to be suitably clamped to the table of a sewing machine, preferably against the lower face thereof. Suitably fastened to the top of the base-plate 1 near its ends and extending part way across it are the side-boards 50 2 which project downwardly beyond the forward edge of the base-plate 1. Interposed between the side-boards 2 at the rear thereof is the transverse board or back-plate 3 arranged at right angles to the base-plate 1. 55 This back-plate 3 is provided with a longitudi-

dinal slot 4 through which the work may pass. Fastened to the outer faces of the side-boards 2 are the inclined arms 5 parallel to each other and connected at their lower ends by the transverse guide-board 6 formed 60 with a slot 6^x to permit the passage of the fabric. The arms 5 are also connected by the transverse guide-board 7 having a slot 8, through which the fabric may pass. A third guide-board 9, having a slot 10 for the goods, 65 is secured to the side-boards 2 and is so positioned as to have its lower edge in contact with the forward edge of the base-plate 1. The guide-boards 7, 9, are parallel to each other, while the boards 9, 3 are inclined at an 70 acute angle each to the other. The side boards 2 are further connected by the cross-bar 11 and the arms 5 are united by a similar cross-bar 12.

Slidably mounted on the bars 11, 12 are 75 the gages 13 formed with openings 14 through which pass these bars. The gages 13 are further formed with the recesses 15 to receive the guide-boards 7, 9, the recesses which receive the guide-board 9 being enlarged, as shown at 16, to permit free movement of the gages 13 (Fig. 2). The rear faces of the gages 13 abut against the back-plate 3. By proper relative movement the gages can be adjusted for goods of different 80 widths; and by moving the gages 13 with relation to the side-boards 2 the goods can be properly positioned with relation to the tucker attachment (not shown). To hold the gages 13 in their adjusted position the 85 clamp pins 17 carried by the gages 13 engage the bars 11, 12.

Fastened to the outer face of each of the side boards 2 and extending rearwardly therefrom is an arm 18 provided with a slot 95 19, through which passes a clamp-screw 20. The latter forms a pivotal connection which permits the arms 18 to be swung out of the way, when not in use; and the slot 19 permits an adjustment to be made with relation to the tucker attachment. The outer ends of the arms 18 are connected by the guide-bar 21, formed with a longitudinal slot 22 through which it is intended the work 100 will pass.

In front of the guide-bar 21, one of the arms 18 is provided with an opening 24 through which passes a gage-carrying rod 25. To one end of the latter is fixed a gage 26 which is formed with a recess 27 to straddle 110

- the guide-bar 21. Between the gage 26 and one of the arms 18 is slidably mounted a second gage, 28, which also straddles the guide-bar 21 in a manner similar to the gage 26.
- 5 The gage 28 is held against movement by the binding pin 29 passing therethrough and engaging the gage-carrying rod 25 and is movable with relation to the gage 26 to accommodate goods of different widths.
- 10 After the gages 26, 28 have been properly adjusted and it is desired to position the goods with relation to the tucker attachment, it is only necessary to give the desired movement to the projecting end 30 of the
- 15 rod 25. When the goods have been brought into the desired position, the rod 25 is held against movement by the binding pin 31.

To give the proper attention to the material, the latter may be passed from in front of the guide-board 7 through the slot 8, thence rearwardly through the slot 6^x, then over the top of the guide-boards 6 and 7 and through the slots 10, 4 and 22.

By placing the right-hand gage 13 close against the right-hand side-board 2, thereby uncovering the slots 8, 10 and 4, the device may be used as a guide for a hemmer attachment, the arms 18 being first thrown upwardly and rearwardly, as explained in a companion application, Serial No. 442,088, filed July 6th, 1908.

I claim:

1. In a guiding device for sewing machines, the combination with supporting frame-members, of a guide-bar carried thereby; gages slidably mounted on said guide-bar; and a gage-carrying rod upon which said gages are mounted free to be adjusted and which is supported in one of said frame-members and freely movable relatively

thereto to carry said gages in their adjusted relation to each other back and forth over said guide-bar.

2. In a guiding device for sewing machines, the combination with supporting frame-members, of a pair of arms mounted free to swing thereon; a guide-bar carried by said arms and formed with a slot; and gages mounted upon said guide-bar.

3. In a guiding device for sewing machines, the combination with supporting frame-members, of a pair of arms mounted free to swing thereon; a guide-bar carried by said arms and formed with a slot; a gage-carrying rod; and gages carried by said rod and slidably mounted upon said guide-bar.

4. In a guiding device for sewing machines, the combination with supporting frame-members, of a pair of arms mounted theron and formed with slots, which permit said arms to be moved relatively to said frame-members; a guide-bar carried by said arms and formed with a slot; and gages mounted upon said guide-bar.

5. In a guiding device for sewing machines, the combination with supporting frame-members, of a slotted guide-board mounted therebetween; a slotted guide-bar mounted on said frame-members, free to be adjusted to and from the same; and gages carried by said guide-bar.

In testimony whereof I have hereunto set my hand at said Potsdam this 1st day of July, A. D., 1908, in the presence of the two undersigned witnesses.

WILBER A. FOX.

Witnesses:

FRANK L. CUBLEY,
M. H. BROWN.
